UNITED STATES PATENT OFFICE.

HIRAM W. HAYDEN, OF WATERBURY, CONNECTICUT, ASSIGNOR TO HOLMES,
BOOTH & HAYDENS, OF SAME PLACE.

DESIGN FOR A LAMP-COLLAR.

SPECIFICATION forming part of Design No. 17,871, dated November 8, 1887.

Application filed October 1, 1887. Serial No. 251,218. Term of patent 7 years.

To all whom it may concern:

Be it known that I, HIRAM W. HAYDEN, a citizen of the United States, residing at Waterbury, in the county of New Haven and State 5 of Connecticut, have invented and produced a new and original Design for Lamp-Collars, of which the following is a specification.

This design has for its object to provide a novel and attractive lamp-collar, as exhibited 10 in the accompanying drawing, the figure in which is a side elevation of the design.

In the drawing, the numeral 1 indicates the lower annular band of the lamp-collar, and 2 indicates the top circular band, these bands 15 being smooth and plain. A row of vertical

ribs, 4, extends around the lamp-collar and constitutes the girdle 3 between the lower and upper bands, 1 and 2.

What I claim is—

The design for a lamp collar, consisting of 20 the lower and upper circular bands, 1 and 2, and the intervening annular row of vertical ribs, 4, composing the girdle 3, substantially as shown and described.

In testimony whereof I affix my signature in 25 presence of two witnesses.

HIRAM W. HAYDEN.
